United States Patent

Des. 236,590
Patented Sept. 2, 1975

236,590

AIRCRAFT CLOCK

David N. Torresdal, 427 Hillcrest Way,
Redwood City, Calif. 94062

Filed Oct. 10, 1973, Ser. No. 405,129

Term of patent 14 years

Int. Cl. D10—01

U.S. Cl. D10—15

FIG. 1

FIG. 4

FIG. 2

FIG. 3

FIG. 1 is a bottom-left-front isometric view of an aircraft clock showing my new design;

FIG. 2 is a front elevational view thereof;

FIG. 3 is a right side elevational view thereof;

FIG. 4 is a top plan view thereof.

The rear of the aircraft clock, not shown, is plain and unornamented.

I claim:

The ornamental design for an aircraft clock, as shown.
